CLEANSING COMPOSITIONS

William Baird, Arthur Hill, John Edmund Guy Harris, Stephen Hellicar Oakeshott, and Wilfrid John Wilson, Manchester, England, assignors to Imperial Chemical Industries Limited, a corporation of Great Britain

No Drawing. Application April 6, 1942, Serial No. 437,880. In Great Britain May 10, 1941

5 Claims. (Cl. 252—98)

The present invention relates to pulverulent cleansing preparations and in particular to that kind of soap powder which also contains a bleaching agent.

It is known to mix together, to give a pulverulent preparation, common soaps; alkali salts such as sodium carbonate, sodium bicarbonate, borax, sodium silicate, trisodium phosphate; and salts of hydrogen peroxide-yielding per-acids, e. g. sodium perborate or percarbonate.

It is known that per-acid salts of this kind are unstable in the presence of alkali and consequently pulverulent preparations of the kind referred to are liable to lose active oxygen even on dry storage and also to lose oxygen too rapidly for efficient bleaching in hot aqueous solution. To overcome this it has been proposed to add certain magnesium salts.

According to the present invention pulverulent preparations of the kind described are rendered stable on storage and less liable to lose oxygen too rapidly in a hot aqueous cleansing bath when there is added to their ingredients a small proportion of a compound of the general formula

wherein the R's signify the same or different o-hydroxy-aryl residues which may carry substituents such as alkyl or alkoxy and the X's signify hydrogen atoms or the same or different alkyl groups.

There may be added to the said pulverulent preparations, for example: bis-(o-hydroxybenzal)ethylene diamine, bis-(2-hydroxy-5-methylbenzal)ethylene diamine, bis-(2-hydroxy-3-methoxybenzal)ethylene diamine, bis-(2-hydroxy-1-naphthal)ethylene diamine or bis-(o-hydroxybenzal)1:2-propylene diamine. The quantity of compound so added may conveniently be about 0.01% calculated on the weight of the said compositions but lower quantities, e. g. about 0.001% and higher quantities, e. g. 0.1%, may also be usefully employed.

The compounds to be added to the ingredients of the said pulverulent preparations according to the invention, e. g. bis-(o-hydroxybenzal)-ethylene diamine, may be added either alone or in conjunction with other compounds having also a stabilising action, e. g. diphenylguanidine, or in admixture with a diluent, e. g. sodium sulphate.

Bis-(2-hydroxy-5-methylbenzal)ethylene diamine is made by the condensation of two molecular proportions of 2-hydroxy-5-methylbenzaldehyde with one molecular proportion of ethylene

diamine. Bis-(o-hydroxybenzal)ethylene diamine and other compounds of the above general formula are similarly made by condensing together the required aldehyde or aldehydes and diamine.

The invention is illustrated but not limited by the following examples in which the parts are by weight.

Example 1

10 40 parts of dry soap powder, 20 parts of sodium carbonate, 10 parts of sodium bicarbonate, 5 parts of borax and 1 part of magnesium sulphate, all the materials being in a finely divided form, are mixed thoroughly together. To 90 parts of the resulting mixture there is then added an intimate mixture of 10 parts of sodium percarbonate and 0.1 part of disalicylalethylene diamine, the whole being thoroughly mixed until it is of uniform composition.

20 The above mixture provides a particularly stable detergent composition. The stability thereof is tested by heating at 35° C. in a humid atmosphere. After a period of 14 days the available oxygen in the detergent composition is es-

25 timated by dissolving a sample in dilute sulphuric acid and titrating with permanganate solution, the available oxygen having been determined in the same way before the composition is heated.

30 In this manner it is found that the detergent composition contains twice as much available oxygen after the test as it does when the disalicylalethylene diamine is omitted from the mixture.

Example 2

35 A detergent composition is made as described in Example 1, there being substituted for the 0.1 part of disalicylalethylene diamine an intimate mixture of 0.09 part of diphenylguanidine and 0.01 part of 40 disalicylalethylene diamine. The detergent composition when tested in the manner described at the end of Example 1 is found to possess a similar stability to that of Example 1.

Example 3

45 40 parts of dry soap powder are mixed with 20 parts of sodium carbonate, 10 parts of sodium bicarbonate, 5 parts of borax and 1 part of magnesium sulphate, the materials being in a finely divided form. To 90 parts of this mixture is added an intimate mixture of 10 parts of sodium percarbonate and 0.01 part of bis-(2-hydroxy-5-methylbenzal)ethylene diamine and the whole thoroughly mixed until uniform.

55 There results an especially stable detergent

composition. The stability thereof is tested by determining the available oxygen before and after heating for 14 days at 35° C. in a humid atmosphere. The available oxygen is determined as described in the latter part of Example 1. In this manner the detergent composition is found to retain four times as much available oxygen after the said test as is the case when the bis-(5-methylsalicylal)ethylene diamine is omitted from the mixture.

Example 4

A detergent composition is made in the manner described in Example 3 except that there is employed in place of the bis-(5-methylsalicylal)-ethylene diamine, the same weight of bis-(3-methoxysalicylal)ethylene diamine. The stability of the composition when tested as described in Example 3 is found to be such that it retains twice as much available oxygen as is the case when the bis-(3-methoxysalicylal)ethylene diamine is omitted from the mixture.

Example 5

A detergent composition is made as in Example 3. 0.01 part of bis-(2-hydroxy-1-naphthal)-ethylene diamine being employed in place of the bis-(5-methylsalicylal)ethylene diamine. A composition is obtained of good stability, retaining nearly three times as much available oxygen as is the case when the bis-(2-hydroxy-1-naphthal)ethylene diamine is not included in the mixture.

We claim:

1. A stabilized pulverulent cleansing composition comprising soap; an alkali salt selected from the group which consists of sodium carbonate, sodium bicarbonate, borax, sodium silicate, and trisodium phosphate; an oxidizing agent selected from the group which consists of sodium perborate and sodium percarbonate; and from 0.001% to 0.1% by weight, based on the total weight of said composition, of a stabilizing agent having the general formula

wherein R represents an o-hydroxy aryl radical selected from the group which consists of unsubstituted o-hydroxy aryl residues, and alkyl and alkoxy ring-substituted o-hydroxy aryl radicals, said R's being the same or different radicals, and X represents a radical selected from the group which consists of hydrogen and lower alkyl radicals.

2. A stabilized purverulent cleansing composi-

tion comprising soap; and alkali salt selected from the group which consists of sodium carbonate, sodium bicarbonate, borax, sodium silicate, and trisodium phosphate; an oxidizing agent selected from the group which consists of sodium perborate and sodium percarbonate; diphenyl guanidine in stabilizing proportion; and from 0.001% to 0.1%, by weight, based on the total weight of said composition, of a stabilizing agent having the general formula

wherein R represents an o-hydroxy aryl radical selected from the group which consists of unsubstituted o-hydroxy aryl radicals, and alkyl and alkoxy ring-substituted o-hydroxy aryl residues, said R's being the same or different radicals, and X represents a radical selected from the group which consists of hydrogen and lower alkyl radicals.

3. A stabilized pulverulent cleansing composition comprising soap; an alkali salt selected from the group which consists of sodium carbonate, sodium bicarbonate, borax, sodium silicate, and trisodium phosphate; an oxidizing agent selected from the group which consists of sodium perborate and sodium percarbonate; and from 0.001% to 0.1%, based on the total weight of said composition, of disalicylal ethylene diamine.

4. A stabilized pulverulent cleansing composition comprising soap; an alkali salt selected from the group which consists of sodium carbonate, sodium bicarbonate, borax, sodium silicate, and trisodium phosphate; an oxidizing agent selected from the group which consists of sodium perborate and sodium percarbonate; and from 0.001% to 0.1%, based on the total weight of said composition, of bis-(2-hydroxy-5-methylbenzal)ethylene diamine.

5. A stabilized pulverulent cleansing composition comprising soap; an alkali salt selected from the group which consists of sodium carbonate, sodium bicarbonate, borax, sodium silicate, and trisodium phosphate; an oxidizing agent selected from the group which consists of sodium perborate and sodium percarbonate; and from 0.001% to 0.1%, based on the total weight of said composition, of bis-(2-hydroxy-1-naphthal)ethylene diamine.
